Filed May 18, 1964, Ser. No. 80,011

Term of patent 14 years

(Cl. D48—20)

FIG. 1

The right side, not shown, is a mirror image of the left side shown in FIG. 1. The electric cord is shown broken away for convenience of illustration.

I claim:

The ornamental design for a portable fluorescent lamp, as shown and described.
